UNITED STATES PATENT OFFICE.

HERMANN WEISSENBURGER, OF CANNSTADT, WÜRTEMBERG, GERMANY.

APPARATUS FOR THE SALE OF LIQUIDS.

SPECIFICATION forming part of Letters Patent No. 417,348, dated December 17, 1889.

Application filed February 12, 1889. Serial No. 299,795. (No model.) Patented in Germany November 24, 1888, No. 48,019; in Luxemburg December 29, 1888, No. 1,070; in France December 31, 1888, No. 195,085; in Belgium December 31, 1888, No. 84,476; in Spain February 4, 1889, No. 9,191; in Italy February 14, 1889, XLIII, 304, XXII, 24,720, and in Switzerland March 1, 1889, No. 500.

To all whom it may concern:

Be it known that I, HERMANN WEISSENBURGER, a subject of the Emperor of Germany, and a resident of Cannstadt, in the 5 Kingdom of Würtemberg, Germany, have invented a new and useful Improvement in Apparatus for the Sale of Liquids, (for which I have obtained patents as follows: in Germany, No. 48,019, dated November 24, 1888; in Italy, 10 Vol. XXII, No. 24,720, Vol. XLIII, No. 304, dated February 14, 1889; in France, No. 195,085, dated December 31, 1888; in Belgium, No. 84,476, dated December 31, 1888; in Spain, No. 9,191, dated February 4, 1889; in Luxemburg, No. 1,070, dated December 29, 1888, and 15 in Switzerland, No. 500, provisional patent, dated March 1, 1889,) of which the following is a specification.

The object of this invention is an apparatus for the sale of liquids, more particularly of perfume, in the shape of spray; and an essential feature of the invention is the application of the coin fed into the apparatus as a medium for transmitting pressure to the bag 20 of the spray-diffuser.

Referring to the accompanying drawings, Figures 1 and 2 are vertical sections. Fig. 3 is a cross-section along line X Y, Fig. 1, of the improved apparatus as inclosed in a casing. 30 Figs. 4 and 5 are vertical sections of the upper portion of the device, on an enlarged scale; and Fig. 6 is a cross-section along line V W, Fig. 4.

The improved apparatus consists of three 35 principal parts, namely:

First, the frame A, containing the coin-feed passage E, the passage E' for ejecting inferior coin, the pressing-rod d, and the bow g.

Second, the cross - piece B, adjustably 40 screwed onto the frame A, and to which is secured the cylinder r. In the latter is provided another cylinder r', carrying at the top a round plate, which is rigidly secured through rods t t to a plate p, and carries at the top a 45 coin-rest b, that receives the coin fed into the passage E and detained by the bow g. The

cylinder r, with the coin-rest b, is held in a suitable position by means of the two helical springs s, surrounding the rods t.

Third, the cross-piece C, likewise screwed 50 onto the frame A, and carrying an india-rubber bag c, with tube c', which leads to a spray-diffuser J, with spout i, situated on the liquid-reservoir R.

I wish it to be understood that the part 55 three of the apparatus is immaterial regarding my invention, that this part is merely specified to explain the action of the apparatus, and that any other suitable device for the direct production of spray may be substituted 60 therefor.

The three principal parts above referred to are inclosed in a casing G, having corresponding openings for the passages E and E'. The passage E' may also be omitted, if it is desired 65 that any coin inferior in size to the prescribed coin, and consequently not detained by the bow g, shall not be ejected or refused, but forfeited.

The pressing-rod d, movable in the frame 70 A and extending through the casing, is round at the upper end and carries a knob K, screwed onto it. It is furthermore surrounded by a helical spring f, serving to return the rod into its normal position after having been 75 pressed down. The upper part of the rod, with helical spring, is surrounded by two tubes guided telescopically in one another. The pressing-rod is beveled at its lower extremity, for the purpose of causing the coin, after 80 the apparatus has been in action, to fall through a corresponding aperture, provided at e e in the frame A, into the coin-receptacle.

The apparatus is operated as follows: The coin dropped in and detained by the bow g 85 lies free on the rest b and directly below the pressing-rod d. On pressing down the knob K sufficiently the rod d comes first in contact with the coin m, and in its progress causes the cylinder r, with rods t t and plate p, to descend, thereby compressing the india-rubber bag c and actuating the spray-diffuser J. 90

The coin, having passed with its upper edge the rim *e e* of the frame *A*, is laterally ejected, owing to the beveled shape of the lower end of the rod, and the action of the apparatus is discontinued, the various parts being returned into their normal position by the action of the springs *s s* and *f*.

What I claim is—

1. The combination, in an apparatus for the sale of liquids, of a pressing-rod *d*, coin-rest *b*, cylinder *r*, rods *tt*, plate *p*, and bag *c*, whereby the coin is allowed to form a medium for transmitting pressure to the latter, substantially as specified.
2. The combination, in an apparatus for the sale of liquids, of rods *tt*, plate *p*, a movable

cylinder *r*, and the coin-rest *b*, substantially as specified.

3. The combination, in an apparatus for the sale of liquids, with plate *p*, cylinder *r*, coin-seat *b*, and rods *tt*, of helical springs *s s*, for returning the coin-seat *b* to its normal position after the ejection of the coin, substantially as specified.

In testimony whereof I have signed this 25 specification in the presence of two subscribing witnesses.

HERMANN WEISSENBURGER.
